US0D1071210S

(12) **United States Design Patent** (10) **Patent No.:** **US D1,071,210 S**
(45) **Date of Patent:** **** Apr. 15, 2025**

(54) **SYRINGE LOCK**

- (71) Applicant: **FEMASYS INC.**, Suwanee, GA (US)
(72) Inventors: **Kathy Lee-Sepsick**, Suwanee, GA (US); **Jeremy A. Sipos**, Alpharetta, GA (US)
(73) Assignee: **Femasys Inc.**, Suwanee, GA (US)
(**) Term: **15 Years**
(21) Appl. No.: **29/881,857**
(22) Filed: **Jan. 6, 2023**

CLAIM

The ornamental design for a syringe lock as shown and described.

DESCRIPTION

FIG. 1 is a rightward perspective view from the bottom of an embodiment of a syringe lock of the present disclosure; FIG. 2 is a leftward perspective view from the top of the device of FIG. 1; FIG. 3 is a bottom view of the device of FIG. 1; FIG. 4 is a top view of the device of FIG. 1; FIG. 5 is a front elevational view of the device of FIG. 1; FIG. 6 is a back elevational view of the device of FIG. 1; FIG. 7 is a left elevational view of the device of FIG. 1; FIG. 8 is a right elevational view of the device of FIG. 1; FIG. 9 is a perspective view of the top of the device of FIG. 1, with the syringe lock engaged with a plunger end; and, FIG. 10 is a perspective view of the bottom of the device of FIG. 1, with the syringe lock engaged with a plunger end. ps The broken lines immediately adjacent to the shaded areas in the figures represent the boundaries of the claimed design. The broken lines in the figures illustrate the portions of the syringe lock that form no part of the claimed design. The other broken lines illustrate environmental subject matter that form no part of the claimed design. None of the broken lines form any part of the claimed design.

1 Claim, 4 Drawing Sheets
